(57) CLAIM

The ornamental design for a combined base and knife sharpener, as shown and described.

DESCRIPTION

FIG. 1 is a perspective view of a combined base and knife sharpener design showing my new design.

FIG. 2 is a front view of a combined base and knife sharpener.

FIG. 3 is a rear view of a combined base and knife sharpener.

FIG. 4 is a left side view of a combined base and knife sharpener.

FIG. 5 is a right side view of a combined base and knife sharpener.

FIG. 6 is a top view of a combined base and knife sharpener.

FIG. 7 is a bottom view of a combined base and knife sharpener; and,

FIG. 8 is a left, rear side perspective view of a combined base and knife sharpener.

The broken lines in the drawings depict portions of the combined base and knife sharpener that form no part of the claimed design.

1 Claim, 8 Drawing Sheets
